(57) **CLAIM**

The ornamental design for an aerial toy, as shown and described.

DESCRIPTION

FIG. 1 is a perspective view from below, to the front and to the right side of a new design for an aerial toy;

FIG. 2 is a perspective view from above, to the rear, and to the left side thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof; and,

FIG. 9 is a variation of a top plan view thereof.

The broken lines shown in the drawings are for illustration only and form no part of the claimed design. The views shown in FIG. 9 illustrates the view of the aerial toy if the dashed outlines shown in the parachute canopy therefrom were apertures.
